United States Patent Office

Des. 206,855
Patented Feb. 7, 1967

206,855

BODKIN

Lena J. Ferla, Jenkintown, Pa., assignor to Inventors League Inc., Bala Cynwyd, Pa., a corporation of Pennsylvania

Filed Oct. 22, 1965, Ser. No. 87,777

Term of patent 14 years

(Cl. D3—19)

Fig.1

The sides of the bodkin opposite those shown in FIGURES 1 and 2 are identical thereto.

I claim:

The ornamental design for a bodkin, as shown and described.
